(57) **CLAIM**

The ornamental design for a crib, as shown and described.

DESCRIPTION

FIG. 1 is an upper perspective view of the crib showing my new design;

FIG. 2 is a front and back elevational view thereof;

FIG. 3 is a left and right side elevational view thereof;

FIG. 4 is a top plan view thereof;

FIG. 5 is an upper perspective view thereof without baseboard and side panels; and,

FIG. 6 is a top plan view thereof without baseboard and side panels.

The broken lines are for environmental purposes only and form no part of the claimed design.

FIGS. 5 and 6 show the baseboard and side panels removed for the convenience of illustration.
